CLAIM

I claim the ornamental design for the customizable baseball hat having snap-on decorative pendant, as shown and described.

DESCRIPTION

FIG. 1 is a side elevation view of the customizable baseball hat, with the snap-on decorative pendant not shown for clarity of illustration;

FIG. 2 is a rear elevation view thereof;

FIG. 3 is a front elevation view thereof;

FIG. 4 is a top plan view thereof;

FIG. 5 is a bottom plan view thereof; and

FIG. 6 is a front perspective view of the claimed design wherein the decorative pendant is shown snapped onto the front of the baseball hat; and,

FIG. 7 is a rear perspective view of the claimed design.

1 Claim, 6 Drawing Sheets
